Primary Examiner — Rhea Shields*(74) Attorney, Agent, or Firm* — Shane Cortesi(57) **CLAIM**

The ornamental design for an power supply device, as shown and described.

DESCRIPTION

FIG. 1 is a front right top perspective view of an power supply device in accordance with the present invention.

FIG. 2 is a rear left bottom perspective view of the power supply device of FIG. 1.

FIG. 3 is a front elevation view of the power supply device of FIG. 1.

FIG. 4 is a rear elevation view of the power supply device of FIG. 1.

FIG. 5 is a left elevation view of the power supply device of FIG. 1, with the right elevation view being a mirror image thereof.

FIG. 6 is a top plan view of the power supply device of FIG. 1; and,

FIG. 7 is a bottom plan view of the power supply device of FIG. 1.

1 Claim, 3 Drawing Sheets*FIG. 1*

FIG. 2

*FIG. 3**FIG. 4*

FIG. 5

FIG. 6

FIG. 7
